(74) Attorney, Agent, or Firm — Chhabra Law Firm, PC

(57) **CLAIM**

The ornamental design for a yoga towel, as shown and described.

DESCRIPTION

FIG. 1 is a top perspective view of a yoga towel, showing my new design;

FIG. 2 is a top view thereof, the bottom view being a mirror image thereof.

FIG. 3 is a right side view thereof, the left side being a mirror image thereof. The broken lines are not shown for clarity of disclosure; and,

FIG. 4 is a front view thereof, the back view being a mirror image thereof. The broken lines are not shown for clarity of disclosure.

The broken lines in the drawings depict the environment in which the claimed design is used. The broken lines depict unclaimed subject matter only and form no part of the claimed design.

1 Claim, 3 Drawing Sheets(56)
